Des. 202,896
Patented Nov. 16, 1965

202,896

FLUSH MOUNTED MANUAL CARD READER

Glenn R. Ekers, Camp Hill, Pa., assignor to
AMP Incorporated, Harrisburg, Pa.

Filed Oct. 21, 1963, Ser. No. 77,072

Term of patent 14 years

(Cl. D26—5)

Fig. 2

Fig. 3

Fig. 4

FIG. 1 is a perspective view of a flush mounted manual card reader, showing my new design;
 FIG. 2 is a front elevational view;
 FIG. 3 is a top plane view; and
 FIG. 4 is a side elevational view thereof.

The dominant features of my new design are shown in solid lines in the drawing.

I claim:

The ornamental design for flush mounted manual card reader, as shown and described.
